UNITED STATES PATENT OFFICE.

GEORGE N. PIFER, OF CLEVELAND, OHIO, ASSIGNOR TO THE AMERICAN AUTOMATIC PHOTOGRAPH COMPANY, OF CLEVELAND, OHIO, A CORPORATION OF OHIO.

AUTOMATIC PHOTOGRAPH-DEVELOPING APPARATUS.

No. 833,626.

Specification of Letters Patent.

Patented Oct. 16, 1906.

Application filed January 5, 1904. Serial No. 187,734.

To all whom it may concern:

Be it known that I, GEORGE N. PIFER, a citizen of the United States, and a resident of Cleveland, Ohio, have invented certain Improvements in Automatic Photograph-Developing Apparatus, of which the following is a specification.

My invention consists of certain improvements in the automatic photographic apparatus forming the subject of my previous patents, Nos. 708,166, 708,167, and 708,168, dated September 2, 1902, the main purpose of my present improvements being to provide for the simultaneous treatment of a number of successively-exposed plates whereby I prevent that waste of time which in the previous machines was permitted to intervene after the exposure had been made and while the exposed plate was being developed and fixed.

In using the present machine the persons desiring to be photographed may succeed each other as rapidly as the exposures are made. Hence the capacity of the machine is very materially increased as compared with the one in which the entire operation of developing and fixing the plate had to be performed before another exposure was possible.

In the accompanying drawings, Figure 1 is a side view of sufficient of an automatic photographic machine to illustrate my present invention. Fig. 2 is a similar view illustrating the parts in a different position from that shown in Fig. 1. Fig. 3 is a plan view. Fig. 4 is a plan view illustrating another embodiment of my invention, and Fig. 5 is a perspective view illustrating still another embodiment of the same.

In Figs. 1, 2, and 3 of the drawings is shown a receptacle having three tanks 1, 2, and 3, the tank 1 being intended for the reception of a developing fluid, the tank 2 receiving a fixing fluid, and the tank 3 containing a washing fluid. Adapted to suitable bearings on the central tank is a transverse shaft 4, upon which is mounted a screw conveyer 5, the lower portion of which is in close proximity to a perforated or other open false bottom 6 in the tank 2, whereby a plate introduced between the convolutions of the conveyer 5 will by the rotation of the latter be fed along on the false bottom 6 of said tank 2 from one end of the latter to the other. At the delivery end of the screw conveyer 5 the latter has be-

tween its convolutions a rib 7. Hence when the plate reaches the final convolution of the screw it is lifted by said rib from the lower portion of the chamber in which the screw operates, so as to be delivered over the edge of the tank 2. The sensitized plates after being properly exposed in the apparatus are fed downwardly through a chute 8, but are prevented from leaving the lower end of the same by an escapement-lever 9, having upper and lower pawls 10 and 11 on opposite sides of the fulcrum of the lever and so spaced as to receive one of the sensitive plates between them. The normal position of this escapement-lever is that shown in Fig. 1, the preponderance of the lower arm of the lever causing its pawl 11 to engage the lowermost plate in the chute 8, and thereby prevent the delivery of said plate therefrom. If, however, the depending arm of the lever 9 is moved outwardly in the direction of the arrow in Fig. 1, the pawl 11 will be moved out of engagement with the lowermost plate in the chute, so as to permit delivery of the latter from said chute; but at the same time the upper pawl 10 of the escapement-lever will be thrust inwardly, as shown in Fig. 2, so as to engage the following plate, and thereby prevent delivery of more than one plate at the time from the chute, said upper pawl being withdrawn when the lever 9 is permitted to swing back again to its normal position, so as to permit of the descent of the plates in the chute, the lower pawl 11, however, arresting the lowermost plate when it reaches the lower end of the chute and the parts being then again in position for permitting delivery of another plate from the chute when the escapement-lever is again moved outwardly. A rock-shaft 12 at the upper inner corner of the tank 1 carries a tray 13, which is located directly beneath the delivery end of the chute 8, and therefore receives each plate as it is delivered from said chute, the tray being then in the depressed position shown in Fig. 2, so that the plate entering the tray will be submerged in the developing liquid contained in the tank 1, the tray being perforated or of other open construction, so that said developing liquid has free access to all portions of the interior of the tray.

The tray 13 is open at the top. Hence when said tray is lifted to position shown in

Fig. 1 a plate will roll from the same into the space between the first two of the convolutions of the conveyer-screw 5, so as to be fed along the tank 2 and exposed to the action of the fixing liquid contained in said tank. On the tray 13 is a projecting lug 30, which when the tray has been again rocked backwardly strikes the depending arm of the escapement-lever 9 and operates the same, so as to permit the lowermost plate in the feed-chute 8 to drop into the tray, the upper pawl 10 engaging the next higher plate and preventing the descent of the same. When the tray 13 again rises, the lever 9 is released from the control of the lug 30 and resumes its normal position, so as to permit the plates to descend in the feed-chute 8, the lowermost plate being caught and retained by the lower pawl 11 of the lever preparatory to a repetition of the operations when the tray 13 is again tilted downwardly. Tank 3 contains a tray 14 similar to tray 13 and, like it, mounted on a rock-shaft 15 at the upper outer corner of said tank 3, this tray receiving the developed and fixed plate delivered by the conveyer-screw 5, and after permitting the same to remain immersed in washing fluid in tank 3 for a proper length of time delivering it from said tank, as shown in Fig. 2. The shaft 4, which carries the conveyer-screw 5, is rotated in any suitable manner, and the joint and simultaneous operation of said conveyer-screw and of the trays 13 and 14 is effected in the manner following: On one end of the shaft 4 of the conveyer-screw is a crank-arm 16, having a pin 17, which engages a pair of links 18 and 19. The link 18 has a slot 20 for receiving a pin 21 on a crank-arm 22, which is secured to the rock-shaft 12 of the tray 13, and the link 19 has a similar slot 23 for receiving a pin 24 on a crank-arm 25, which is secured to the rock-shaft 15 of the tray 14. Continuous rotation of the shaft 4, therefore, provides for the rocking of the trays 13 and 14, each of the trays, however, being permitted to remain in the depressed position for a considerable length of time, owing to the lost motion of the links 18 and 19, provided for by the slots in said links. The conveyer-screw 5 provides for the accommodation of as many plates as there are spaces between the convolutions of said screw. Hence any desired number of plates may be subjected simultaneously to the action of the fixing-bath, and each plate may be retained in said bath for a period of time necessary to effect its complete fixation, such period of time being considerably longer than that necessary to effect either the prior development or subsequent washing of the plate.

While I prefer in carrying out my invention to use a single fixing-tank and single conveyer-screw, as previously shown and described, a plurality of fixing-tanks may be employed, if desired, each with its own con-

veyer. For instance, in Fig. 4 I have shown apparatus in which three fixing-tanks 2, 2^a, and 2^b are employed, the conveyer in the first tank receiving the plate from the tray 13 and conveying it through the tank in one direction and the conveyer in the intermediate tank 2^a receiving the plate from the conveyer in the first tank and conveying it in the opposite direction, the conveyer in the final tank 2^b receiving the plate from the conveyer in the intermediate tank and conveying it in the opposite direction to the point at which it is delivered to the tray 14 in the washing-tank. In Fig. 5 I have illustrated still another embodiment of my invention in which the trays and conveyer screw or screws are no longer employed, this device comprising a series of tanks 1, 2, 2^a, and 3, each with slotted, perforated, or other open false bottom. In connection with each tank operates a rotating fork 26, carried by a transverse shaft 27, all of these shafts being geared to a single longitudinal shaft 28. Hence by the rotation of the latter rotating movement will be simultaneously imparted to all the forks 26. The position of the various forks upon the respective shafts is such that the desired timing of their successive operations will be effected. Thus a plate delivered onto the false bottom of the tank 1 remains thereon for a short time and is then caught by the first fork 26, coöperating with said tank, and is carried forwardly and fed into the tank 2, wherein it remains for a certain time before being ejected therefrom and fed into the tank 2^a by the action of the second fork 26, the plate being allowed to remain for a certain time in tank 2^a and then being fed by the third fork 26 into tank 3, from which, after it has been retained therein for a sufficient time to effect the desired washing of the plate, it is delivered by the final fork 26 of the series. In all these embodiments of my invention, however, provision is afforded for acting simultaneously upon a succession of plates, each plate remaining for a longer time in the fixing-bath than in either the developing or washing baths, as is desirable in the proper and orderly operation of the machine.

The term "bath" as used in my claims is not to be interpreted as limiting same to a single chamber, vessel, or receptacle unless the claim is otherwise limited in that respect.

It will be evident from what I have shown that other embodiments of the main feature of my invention can be devised by those skilled in the art. Hence my broader claims are not to be understood as limited to specific mechanism.

I claim—

1. An automatic photographic machine having a treating-bath, and means for moving a plurality of rigid plates simultaneously through one and the same bath, substantially as specified.

2. An automatic photographic machine having a developing-bath and a fixing-bath, with means for subjecting the plates singly to the action of the developing-bath, and for subjecting a plurality of plates simultaneously to the action of the fixing-bath, substantially as specified. 45
3. An automatic photographic machine having a developing-bath, a fixing-bath, and a washing-bath, with means for subjecting the plates singly to the action of the developing and washing baths, and for subjecting a plurality of plates simultaneously to the fixing-bath, substantially as specified. 50
4. An automatic photographic machine having a treating-bath provided with a screw conveyer for moving the plate through said bath, substantially as specified. 55
5. An automatic photographic machine having a treating-bath provided with a screw conveyer for moving a plate through said bath, said conveyer having a lifting member for discharging the plate from the bath, substantially as specified. 60
6. An automatic photographic machine having a plurality of treating-baths, a screw conveyer in one of said baths, and a tilting tray for conveying a plate from the preceding bath to said screw conveyer, substantially as specified. 65
7. An automatic photographic machine having a plurality of treating-baths, a screw conveyer in one of said baths, and a tilting tray in a succeeding bath for receiving a plate from said conveyer, substantially as specified. 70
8. An automatic photographic machine having a plurality of treating-baths, a screw conveyer in one of said baths, a tilting tray in another of said baths, and means for effecting simultaneous rotation of the screw conveyer and tilting of the tray, substantially as specified. 75
9. An automatic photographic machine having a plurality of treating-baths a rotating screw conveyer in one of said baths, a tilting tray in another of said baths, crank-arms on the conveyer-shaft and on the shaft of the tray respectively, and a slotted link connecting-pins on said crank-arms, substantially as specified. 80
10. An automatic photographic apparatus having, in combination, means for developing and fixing an exposed plate, a plate-feeder, and a stop for preventing delivery of more than one plate at a time from said feeder, one of the elements of the developing and fixing mechanism acting upon said stop so as to release the same, substantially as specified. 85
11. An automatic photographic apparatus having in combination means for developing and fixing an exposed plate, and a plate feeder having an escapement-lever with oppositely-disposed pawls for engaging alternately the lowermost plate in the feeder and the plate next above the same, substantially as specified. 90
12. An automatic photographic apparatus having in combination means for developing and fixing an exposed plate, a plate-feeder, and an escapement-lever therefor having oppositely-disposed pawls for engaging alternately the lowermost plate in the feeder and the plate above the same, one of the elements of the developing and fixing mechanism acting upon said escapement-lever to effect delivery of the plates successively from the feeder, substantially as specified. 95

In testimony whereof I have signed my name in this specification in the presence of two subscribing witnesses.
